AUTOMATIC WINDOW.

No. 578,475.

Patented Mar. 9, 1897.

UNITED STATES PATENT OFFICE.

WILLIAM W. TIDD, OF JACKSONVILLE, FLORIDA.

AUTOMATIC WINDOW.

SPECIFICATION forming part of Letters Patent No. 578,475, dated March 9, 1897.

Application filed February 4, 1896. Serial No. 578,041. (No model.)

To all whom it may concern:

Be it known that I, WILLIAM W. TIDD, a citizen of the United States, residing at Jacksonville, in the county of Duval and State of Florida, have invented a new and useful Automatic Window, of which the following is a specification.

This invention relates to an improvement in windows, and is designed especially for use upon railway and street cars, being, however, easily adaptable to public buildings and private dwellings, steamboats, steamships, &c.

The object of the present invention is to provide an automatic window which will be thoroughly dust and rain proof and thus dispense with the use of double windows in sleeping-cars, at the same time dispensing with all weights, cords, or pulleys. A window constructed as herein contemplated will also obviate all sticking or jamming, is self fastening or locking, will not rattle, and combines simplicity with ease of operation and is capable of any desired degree of ornamentation.

To this end the invention consists in certain novel features and details of construction and arrangement of parts, as hereinafter fully described, illustrated in the drawings, and finally pointed out in the claims.

In the accompanying drawings, Figure 1 is a perspective view of the improved window and its frame complete ready for insertion in the frame of a car-body or other structure. Fig. 2 is a similar view looking from the opposite side, the sash being partly raised. Fig. 3 is a vertical transverse section showing the window and its frame applied to a car-body. Fig. 4 is an enlarged longitudinal section through the spring-roller. Fig. 5 is a detail perspective view of the spring-block. Fig. 6 is a similar view of the central portion of the roller-spring. Fig. 7 is a detail vertical section through the window-fastener. Fig. 8 is a detail horizontal section through one side of the window-casing. Fig. 9 is an enlarged detail cross-section through the spring-roller, taken centrally. Fig. 10 is a detail perspective view of the sash-check used in connection with the improved window, showing portions of the window sash and frame in section.

Similar numerals of reference designate cor-

responding parts in the several figures of the drawings.

Referring to the drawings, 1 designates the window frame or casing, which is preferably cast or otherwise formed of a single piece of metal. I prefer to use aluminium in the construction of the window casing and sash to be hereinafter more particularly described; but the said parts may, however, be formed of iron, steel, brass, or other metal, and nickel-plated or burnished or given any other desired ornamental finish. In this way the sash and its frame may be primarily fitted together with the utmost nicety, and thereafter all rattling and admission of dust, rain, &c., will be obviated, and at the same time, on account of the non-liability of the sash and its frame to swell or be otherwise affected by the weather, there will be no chance of the sash sticking or jamming within the frame, which would interfere with the easy working of the same—an annoyance frequently encountered in railway and street cars as constructed at the present day.

The window-frame 1 is of open rectangular form, and of course is constructed of the particular size desired and also has a transverse extent equal to the thickness of the double wall in which it is located, including the intervening space between such double wall. The window-frame 1 is also provided at about its transverse center with an inwardly-projecting flange 2, extending vertically upon both sides of the frame and also across the base or sill of the frame, as shown. This flange is preferably formed integrally with the main frame or casing 1, and is provided in its inner edge with a longitudinal groove 3. The groove in the lower horizontal connecting portion of the flange 2 extends downwardly entirely through said flange and the sill of the window-frame, communicating with the space between the double walls, so that any dust, dirt, or rain which may progress inwardly as far as said groove or opening will descend therethrough and be prevented from entering within the car.

The window-sash (indicated at 4) fits snugly between the vertical portions of the flange 2 and rests upon the connecting horizontal portion of the flange, and, when elevated, works

through a slot 5, extending longitudinally and about centrally of the top or cap piece of the window-frame. The grooves 3 in the inner edges of the vertical portions of the flange 2 open out through the cap-piece of the window-frame and receive beads or tongues 6, projecting laterally from the opposite edges of the side bars of the window-sash, said tongues extending longitudinally of such side bars and being preferably formed integrally therewith, the said window-sash, as heretofore stated, being cast or otherwise formed from a single piece of metal. The bottom rail of the sash has also formed thereon a downwardly-projecting tongue 7, formed as a continuation of the side tongues 6, and adapted to enter the groove or opening in the horizontal connecting portion of the flange 2 when the sash is closed. The tongues or beads 6 and 7 serve as cut-offs for the dust, cinders, rain, &c., and as they fit snugly within their respective grooves the admission of such matter to the interior of the car or other structure is rendered impossible. The sash 4 is constructed so that its top rail projects a considerable distance above the plane of the upper surface of the cap of the window-frame, as shown at 8, thereby preventing the admission of dust, &c., at this point.

In order to provide for the introduction of a pane of glass, the vertical side rails of the window-sash are rabbeted, as indicated at 9, and the top rail of the sash is formed in its lower edge with a groove 10, the latter being in effect an upward extension of the rabbets 9. The groove 10 is made of sufficient depth to allow the pane of glass to be moved upwardly until its lower edge passes above the upper edge of the lower rail of the sash, and as such lower rail is formed with a groove 11 the glass may descend into such groove, but not sufficiently, however, to withdraw its upper edge out of engagement with the groove 10. After the glass is introduced in the manner just described the edges thereof may be puttied or otherwise secured to prevent rattling and breakage.

In order to still further guard against the passage of dust, &c., through the opening 5 in the top of the window-frame, a deflecting-strip 12 of a right-angular shape in cross-section and having its hypotenuse hollowed or concaved is located in the corner between the cap-piece of the window-frame and the vertical portions of the flange 2, exteriorly of the sliding sash, as shown. This directs the dust, &c., downward and prevents its upward passage through the opening 5. The vertical side rails of the window-sash 4 are extended some distance above the top rail of the sash, and these upwardly-extended ends, as well as the entire length of said side bars, are formed with indentations or sockets 13, whereby each of said side rails is constituted a rack-bar, the same being adapted to coöperate with the teeth of a spring-roller which will now be described.

The spring-roller (indicated at 14) is in the form of a hollow cylindrical shell or tube of any convenient diameter and of a length corresponding to the distance between the opposite side portions of the window-casing 1, the latter being extended upwardly above the cap-piece of the window-frame and provided with open slots 15 to receive the spindles upon which said roller turns. The roller 14 is provided adjacent to each end with a surrounding annular collar 16, fast thereon or formed integrally therewith, as preferred, the said collars being provided each with a peripheral series of teeth 17, which engage the sockets 13 in the side rails of the sash, so that when the roller revolves the sash will slide up or down. The roller 14 is extended beyond the collars 16 and threaded to receive caps 18, of metal, which are screwed thereon, the said caps being closed at their outer ends, with the exception of a small central circular aperture, which forms a bearing-opening for the spindle at that end of the roller.

19 designates a cylindrical block which occupies a position within and centrally of the roller 14, being of less diameter than the internal diameter of said roller and formed with a longitudinal peripheral rib 20, which cooperates with a similar rib 21 within the bore of the roller for preventing the rotation of said block. The opposite ends of this block are turned down or reduced in diameter, as shown at 22, to form seats for the central portion of the power-spring, (indicated at 23.) The spring 23, although formed of a single piece of wire, is what may be termed a "compound" spring, being spirally wound in reverse directions each way from the center. The central portion of the spring is left straight, as at 24, and such straight portion is received in a longitudinal groove 25 in the block 19, being held therein by soldering, if desired. The inner ends of the coiled portions of the spring surround the reduced extremities of the block 19, and such extremities are also formed with concentric end sockets 26, which receive the inner adjacent ends of the spindles 27. The outer ends of the spindles are formed with grooves or sockets 28 for the reception of the opposite terminals of the spring 23, and the extremities of the spindles are flattened, as shown, for entrance in the slots 15 of the window-frame. When the roller is in position, set-screws 29, passing through the window-frame, are brought to bear against the flattened extremities of the spindles, thus holding the roller securely in place.

The roller and its several parts having been assembled in the manner above described, said roller is inserted into the slots 15 of the window-frame and secured by the set-screws 29. The roller is now turned inward toward the window until the spring 23 has been sufficiently wound to exert a force about equal to the weight of the window-sash. The window-sash is now introduced through the open-

ing 5 in the top of the window-frame, the sockets in its side rails engaging the teeth 17 of the roller. In the downward progress of the sash the spring 23 is wound still further, and it will be seen that when the sash is released the 5 spring-roller will serve to lift the sash without any further attention on the part of a passenger.

The sash is held closed down by means of 10 a spring-catch 30. This catch comprises a spring 31, secured to the flange 2 just above the window-sill and centrally thereof, the said spring being recurved to form an inclined spring-flap 32, having at its extremity a button 33, by means of which it may be manipulated, the said button projecting normally 15 through an opening 34 in a retaining-plate 35, secured over the spring 31 and assisting in fastening the same in place. Secured to the 20 bottom rail of the sash is a keeper 36, having a finger-pull 36^a and an offset or hollowed central portion 37, adapted to pass over and embrace the recurved spring 31. The keeper is provided with a spur or projection 38, which, 25 when the sash is down, engages a perforation 39 in the inclined flat portion of the spring 31. The spring-catch is thus automatic in its action and may be easily released by simply pressing upon the button referred to. When 30 this is done, the spring-roller 14 immediately acts to raise the sash in the manner above described. The spring 23 is ordinarily wound sufficiently only to but little more than overbalance the weight of the sash. The hoisting 35 of the sash will thus be gradual and not abrupt and will be the easier to pull down, there being less resistance to overcome.

The window and its sash, where intended for use in cars, are preferably made of metal, as 40 before stated, but for residences and buildings may be made of seasoned wood, with the exception of the spring-roller and its attachments, which should always be of metal to insure strength and reliability. The roller 45 and the sockets 13 in the sash are ordinarily upon the outside, but in extremely cold climates their order may be reversed, they being located upon the inside.

40 designates a sash - check which 45 comprises a sheet-metal frame 41, having at its lower end spaced eye-bearings 42, in which are journaled the opposite transverse portions of a bail-shaped lever or latch 43. At its upper end this lever has pivotally connected thereto a reciprocating pin or bolt 44, which passes through the flange 2 of the window-casing and engages at its inner extremity with any one of a series of notches 45, formed in the bead or tongue 6 of the window-sash. 50 The lever 43 also carries at its upper end rubber bumpers or cushions 46 to deaden the noise of the clicking of the check, and the lower arm of the lever has interposed between it and the frame 41 a retracting-spring 47, which serves to uphold the depending operating-chain 48 and to press the pin or bolt 44 toward the sash 4. The frame 41 is ex-

tended at its upper edge to form a stop-arm 49 for limiting the outward movement of the lever and the pin or bolt 44, and finally a 55 ring or pull 50 is attached to the lower end of the chain 48 for convenience in operating the same. By pressing upon the button 33 the sash is released and drawn upward by the spring-roller until the first notch 45 in the 60 sash reaches the bolt 44, whereupon said bolt drops into the notch. By now pulling upon the chain 48 the sash will continue to ascend until the chain is again released. When it is desired to lower the sash, the finger-hold 65 36^a is grasped and moved downward, and by reason of the inner end of the bolt 44 being beveled from the upper side it will not catch in the notches so as to interfere with the lowering of the sash. 70

From the foregoing description it will be seen that a self-raising window is provided which is thoroughly dust and rain proof and which dispenses with weights, cords, or pulleys and renders it unnecessary to employ 75 double windows in sleeping-cars, &c. The window constructed in accordance with the foregoing description will not stick or jam, will not rattle, is extremely easy in its operation, and may be stopped at any desired elevation. 80

Changes in the form, proportion, and minor details of construction may be resorted to without departing from the spirit or sacrificing any of the advantages of this invention. 85

Having thus described the invention, what is claimed as new is—

1. A window-sash provided with tongues or beads extending longitudinally of its edges, in combination with a window-casing having 105 side grooves in which said tongues or beads move, and also having an opening in its sill portion, the said opening extending longitudinally of the sill and downward entirely through the same and adapted to receive the 110 tongue or bead on the bottom rail of the sash, substantially as described.

2. The combination with a window-frame having a longitudinal slot or opening in its sill, of a sliding sash provided as to its bottom edge with a depending longitudinal tongue adapted to enter the slot or opening in the sill, said slot or opening extending downward entirely through the sill, substantially as and for the purpose described. 115

3. In a window, a window-frame having a flange extending longitudinally of the sill and projecting upward therefrom, said flange being provided with an opening or slot extending entirely through it and the sill, in combination with a sliding sash having a tongue or bead on its bottom edge adapted to enter said opening or slot, substantially as described. 120

4. The combination with a sliding window-sash having side rails extending above its top rail, said side rails and their extending portions each having a vertical series of indentations in one of the exposed faces thereof, and the casing within which said sash is 125 130

mounted to slide, of a spring-roller extending parallel to the sash and provided at or near each end with fixed peripheral teeth adapted to engage said indentations, said roller being supported in the casing in such position that its peripheral teeth engage the indentations in the extended portions of the side rails when the sash is closed, and a locking device to hold the window in its closed position against the force of the spring-roller, substantially as described.

5. The combination with a sliding sash, and means for giving the same a normal upward tendency, of a sash-check consisting of a bail-shaped elbow-lever, a metal frame or clip secured to the casing and having said lever journaled therein and also provided with a

stop-arm for limiting the movement of the lever, a reciprocating bolt carried by one arm of the lever and adapted to engage the sash, a spring interposed between the lever and the frame for holding the bolt normally in engagement with the sash, and an operating connection attached to the lever and extending to within reach of an attendant, whereby the check may be thrown out of action, substantially as described. 20 25

In testimony that I claim the foregoing as my own I have hereto affixed my signature in the presence of two witnesses.

WILLIAM W. TIDD.
